UNITED STATES PATENT OFFICE

2,508,280

ELECTRON TUBE

Fritz Lüdi, Baden, Switzerland, assignor to "Patel-hold" Patentverwertungs- & Elektro-Holding A.-G., Glarus, Switzerland

Application March 17, 1945, Serial No. 583,220
In Switzerland February 1, 1944

Section 1, Public Law 690, August 8, 1946
Patent expires February 1, 1964

15 Claims. (Cl. 250—27.5)

1

The present invention concerns electron tubes for ultra short electromagnetic oscillations which have at least a cathode, an anode consisting of segments biased positively with respect to the cathode, and a magnetic field, there being a high frequency alternating voltage between neighbouring anode segments, and where according to the invention at a distance which is approximately constant from the anode a guide electrode is provided which at least over its greatest part is not penetrated by the electrons, the electrons following paths between the guide electrode and the anode.

In the ultra short electric wave range three fundamentally different kinds of tube types are known, namely retarding field tubes, magnetron tubes and the Klystron. The tube according to the invention is on account of its method of operation comparable with transit time tubes with density-modulated electron beams, but still more so with magnetron tubes. Nevertheless when compared with such tubes there are very pronounced and important differences so that it forms a fundamentally new tube type for the ultra short wave range.

The method of operation of the tube is such that the electrons emitted from the cathode pass to a space bounded by the auxiliary electrode and the anode, where they are subjected to the alternating field prevailing between the anode segments, the constant field existing between the anode and the cathode or guide electrode, and to the applied magnetic field. The electrons move under the influence of these fields along paths between the anode and the guide electrode. The alternating field at the anode segments causes velocity modulation of the electrons which as these latter move onwards changes into a density modulation. The bunches of electrons then react back on to the anode segments and promote charges on these latter by means of which the high frequency oscillations are generated. The tube can also be used in receiving arrangements to amplify electrical oscillations.

The tube has several important advantages. The cathode is of a simple construction. A good vacuum can be obtained without difficulty. The return heating which occurs in magnetron tubes due to the electrons and positive ions and is a considerable disadvantage, is avoided in this new tube, because due to their passing between the guide electrode and the anode the electrons do not return to the immediate vicinity of the hot cathode after each oscillation, and the positive ions mostly fall on to the auxiliary electrode in-

2

stead of on the hot cathode. The path of the electrons from the cathode to the anode can have any length. Furthermore the size of the tube for oscillations in the centimetre wave range is not unfavourably small. Finally an optimum efficiency is reached which is not exceeded by a magnetron tube.

A number of constructional examples of the invention are illustrated in the accompanying drawing, Figs. 1 and 2 showing the essential elements of a tube in perspective view and cross-section respectively, Figs. 3-6 show various constructional forms of the cathode and guide electrode in section, Fig. 7 is a substantially axial section through an electron tube embodying the invention, the section being taken on the plane of line 7—7 of Fig. 8; Fig. 8 is a transverse section through the same on the plane of section line 8—8 of Fig. 7; and Fig. 9 is a perspective view of another embodiment of the invention.

In Fig. 1 a cavity resonator assembly for a tube of cylindrical design is shown, 1 being the electron-emitting hot cathode, 2 a guide electrode and 11 a cavity resonator at anode potential. The resonator 11 is bounded by the outer cover 3, two end walls 4 and by the anode segments 5. There is also a magnetic field in the direction of the axis 6 which is indicated in Fig. 2 by the pole pieces N and S. Guide electrode 2 has the same potential as cathode 1 so that there is a cavity resonator assembly for a constant electrical field which is directed outwards.

During operation the electrons emitted from cathode 1 travel under the influence of the radial electrical and axial magnetic field along cycloidal paths between the guide electrode 2 and the anode segments 5 in the circumferential direction of the micro-wave tube. When resonator 11 oscillates, opposed positive and negative charges occur alternately between neighboring segments 5, which represent the capacity of the cavity resonator, so that a high frequency alternating field exists between these segments. This alternating field causes, as in a Klystron, the velocity of the electrons to vary, whereupon the electrons as they move onwards form bunches or groups. This variation in density in turn results in an increase of the high frequency alternating field between the anode segments, so that the oscillations become stronger. The electron bunches which have given up their energy, finally reach the anode.

Generally practically all the electrons after a complete revolution about the axis of the electron tube will either be absorbed by the guide electrode or will have removed themselves far away from

this electrode, so that no more can reach the hot cathode 1 and thus there will be no return heating from the electrons, such as otherwise occurs in magnetron tubes. Also the return heating by positive ions which may exist as a result of the residual gas is practically negligible, because these ions are completely caught by the guide electrode 2.

The efficiency of the tube is determined by the relationship between the width of the anode segments and the distance of these latter from the guide electrode, and the wave length of the generated oscillations is at a first approximation a function of the mutual capacitance of the anode segments per unit of length in the circumferential direction, of the distance of segments 5 from casing 3 in Fig. 1, and of the axial length of the cavity resonator. Since also constructional aspects play a part in the dimensioning of the segments, the number of such segments can vary very greatly in different tubes. The number of segments and thus the power of the tube can for the same wave length be increased almost indefinitely. This is a fundamental advantage of the tube according to the invention when compared with known types of micro-wave generators.

Another constructional example of the invention is illustrated in Fig. 2 in cross-section. The same reference numerals are used as in Fig. 1. In this case the cathode is constructed as a spiral. Furthermore end plates 7 are provided which are galvanically connected with the auxiliary electrode 2 for the purpose of preventing high frequency power radiation losses and an undesirable diversion of the electrons. A conductive loop 8 is provided for power collection.

The construction of the cathode and guide electrode is important. Various constructional forms of these elements are illustrated diagrammatically in Figs 3-6, where 1 again represents the cathode. In Fig. 3 guide electrode 2' encloses the cathode at the side furthest away from the anode and is thus fully closed in the circumferential direction. In Figs. 4 and 5 a control electrode is provided which is preferably given a negative potential relative to the guide electrode. The control electrode may be a strip 9 located inwardly of the cathode 1, as in Fig. 4, or may be a channel member 9' with flanges at opposite sides of the cathode, as in Fig. 5. The control electrode can be made like a Wehnelt cylinder. When, as shown in Fig. 6, the guide electrode 2'' has turned-in edges 10, it is advisable to give cathode 1 a negative bias relative to electrode 2''. The guide electrode or electrodes 2a can also be so formed that in the vicinity of cathode 1 or control electrode 9, the cathode does not lie in the plane of guide electrode 2a but slightly outside of it. Control electrodes 9 can be given a constant or variable potential. The voltage between cathode and guide electrode can also be variable.

A constructional embodiment of the invention, and of the plural cathode, plural guide electrode type of Fig. 4, with four cathodes 11' and four guide electrodes 12, is illustrated in Figs. 7 and 8. The cavity resonator is provided by an outer cylindrical wall 13 which extends beyond the annular walls 14 on which the anode segments 15 are mounted in alternation. The wall 13 forms a part of the envelope of the tube and its opposite edges are sealed into glass or ceramic rings 16, 17 into which cup-shaped end closures 18, 19 of non-magnetic metal are sealed. The wall 13 is provided with a slot 20 through which a cou-

pling loop 8 extends into the cavity resonator, and the continuity of the evacuated envelope is preserved by a tube or sleeve 21 which surrounds the loop leads and is soldered or welded to the cylindrical wall 13, the outer end of the tube 21 being closed by a glass or ceramic dome 22 in which the loop is sealed.

The cathodes 11' are of spiral type each having one terminal connected to a disk or spider 23 on a lead-in rod 24 which extends through a glass or ceramic dome 25 closing the inner end of a metal tube or sleeve 26 which is soldered or otherwise sealed to the end closure 19. The other end of each cathode 11' is soldered to a cup or spider 27 which is secured to the end closure 19 by screws 28. The guide electrodes 12 are soldered or welded to a cup-shaped support 29 which is secured to the other end closure 18 of the envelope by screws 30.

In another embodiment of the invention, as shown in Fig. 9, a cavity resonator 11 as illustrated in Fig. 1, is supported within an evacuated glass envelope 31 by a lead-in wire 32 and metal strap 33. The cathode rod 1 is supported eccentrically of the resonator axis by metal straps 34 which extend through and are sealed in the glass press 35. A control electrode 9 is supported adjacent the cathode by its lead-in wire or rod 36 and the cylindrical guide electrode 2 is mounted on and supported by its lead-in wire or rod 37. Terminal wires are connected to the several lead-in wires or straps for applying energizing potentials to the several electrodes, and the direct current potential on the guide electrode may be the same as or different from the cathode potential.

The cathode can be a spiral or in the form of a hot filament or large surface cathode; it can be heated directly or indirectly. It consists either of one, or with high power tubes, of several filaments or spiral-shaped emitting cathode conductors which are arranged directly next to or along the circumference of the guide electrode, see Fig. 4.

The guide electrode can be given either a constant or variable potential depending upon conditions.

If necessary additional control grids can be provided.

The anode segments generally consist of sheet metal, wires or rods, with elliptical, circular or rectangular cross-section.

The oscillation element is generally a cavity resonator because this involves only small electrical losses and possesses other well known advantages. Its shape can, however, differ considerably from those shown in the drawing. In certain cases a Lecher wire can also be used to advantage for the oscillations.

Those elements which are subjected to heat stresses can for instance be cooled by radiation by painting them black. Their surfaces can also be enlarged by cooling fins. Particularly with high-power tubes it is advisable to provide water cooling. For those parts which are especially subject to heat stresses a special heat-resistant material, for instance tantalum, is used.

The natural frequency can be varied by altering the volume of the cavity resonator. This can also be achieved by varying the penetration of field displacing means at the point where there is a large magnetic or electric energy, or the capacity of the resonator can for instance be varied by varying the mutual capacity of the anode segments. Another possibility for varying the frequency is to change the tuning of a Lecher line 75 which is coupled to the resonator. Finally the

strength of the magnetic field, or the anode voltage, or both, can be made variable for certain purposes.

I claim:

1. An electron tube for ultra high frequency electromagnetic oscillations comprising, within a tube envelope, a hollow cavity resonator having inner and outer cylindrical walls connected by end walls, the inner cylindrical wall being divided by a zig-zag slot into a plurality of pairs of parallel anode segments connected in alternation to the respective end walls, a cathode extending longitudinally of the cylindrical space defined by said anode segments and supported eccentrically of the axis of said cylindrical space, guide electrode means having a circumferential gap in which said cathode is located and spaced at a substantially constant radial distance from said anode segments to define therewith an annular space within which electrons emitted by said cathode may travel, said cavity resonator and anode segments being adapted to be positively biased with respect to said cathode and guide electrode means, said guide electrode means comprising a cylindrical electrode having a circumferential length in excess of the circumferential length of a plurality of adjacent anode segments, and means external to said tube envelope to establish a magnetic field within and parallel to said cylindrical assembly of anode segments.

2. An electron tube as recited in claim 1, wherein said guide electrode means comprises a single cylindrical surface coaxial with the cylindrical assembly of anode segments and with longitudinal edges terminating adjacent said cathode.

3. An electron tube for ultra high frequency electromagnetic oscillations comprising, within a tube envelope, an electron-emitting cathode a hollow cavity resonator having as an inner cylindrical wall, an anode comprising a plurality of pairs of parallel segments adapted to be biased positively with respect to said cathode, said segments being a cylindrical assembly and said cathode being positioned eccentrically of said cylindrical assembly, and a guide electrode comprising a cylindrical portion coaxial with said cylindrical assembly of anode segments, the ends of the cylindrical portion terminating adjacent said cathode.

4. An electron tube as recited in claim 3, wherein an integral portion of the guide electrode connects the ends of said cylindrical portion and is located inwardly of said cathode.

5. An electron tube as recited in claim 3, wherein radial flanges extend inwardly from the ends of the cylindrical portion of said guide electrode.

6. An electron tube as recited in claim 3, wherein electrode means is arranged at the side of said cathode opposite the anode segments adjacent thereto.

7. An electron tube as recited in claim 3, wherein a control electrode is arranged at the side of said cathode opposite the anode segments adjacent thereto.

8. An electron tube as recited in claim 3, wherein a control electrode is arranged at the side of said cathode opposite the anode segments adjacent thereto; said control electrode having radial

flanges extending to opposite sides of, and in spaced relation to, said cathode.

9. An electron tube comprising a plurality of electron-emitting cathodes, a plurality of pairs of anode segments substantially parallel to said cathodes in a cylindrical assembly and adapted to be biased positively with respect to said cathodes, said cathodes being spaced along and equidistant from the surface defined by said anode segments, and guide electrode means spaced substantially uniformly from said anode segments in the circumferential gaps between adjacent cathodes and forming with said anode segments a path for electrons emitted by said cathodes, the number of cathodes and guide electrode means being substantially less than the number of pairs of anode segments.

10. An electron tube as recited in claim 9, wherein said anode segments are arranged in a cylindrical assembly, said cathodes are positioned eccentrically with respect to said cylindrical assembly, and said guide electrode means include a plurality of cylindrical portions coaxial with said cylindrical assembly of anode segments.

11. An electron tube as recited in claim 9, in combination with electrode means located radially inwardly of the several cathodes.

12. An electron tube as recited in claim 9, wherein said anode segments constitute a portion of a cavity resonator.

13. An electron tube as recited in claim 9, in combination with lateral plates electrically connected to said guide electrode means to limit the electron path, said plates being perpendicular to the magnetic field.

14. An electron tube as recited in claim 3, in combination with lateral plates electrically connected to said guide electrode to limit the electron path, said plates being perpendicular to the magnetic field.

15. An electron tube as recited in claim 3, in combination with lateral plates of annular form electrically connected to said guide electrode to limit the electron path, said plates being perpendicular to the magnetic field.
